Patented Oct. 3, 1961

191,466

DUST PAN

John F. Reichlein, 8642 SE. Holgate Blvd.,
Portland, Oreg.

Filed Oct. 27, 1959, Ser. No. 58,085

Term of patent 14 years

(Cl. D44—18)

FIG. 1

FIG. 2

FIG. 3

FIGURE 1 is a perspective view of a dust pan showing my new design.

FIGURE 2 is a rear elevational view of FIGURE 1, and

FIGURE 3 is a fragmentary side elevational view of the left side of FIGURE 1.

I claim:

The ornamental design for a dust pan, substantially as shown.
